UNITED STATES PATENT OFFICE.

CHARLES D. HAEUSLER, OF KRESSBRONN, GERMANY, ASSIGNEE OF ONE-THIRD TO WALTER AUFPFERDIDE, OF ST. LOUIS, MISSOURI; ONE-THIRD TO OSCAR C. HEISLER, OF CHICAGO, ILLINOIS; AND ONE-THIRD TO CHARLES F. HEISLER, OF PHILADELPHIA, PENNSYLVANIA.

APPARATUS FOR ACTIVATING FLUIDS WITH THE EMANATIONS OF RADIO-ACTIVE MATERIAL.

1,098,623.

Specification of Letters Patent.

Patented June 2, 1914.

Application filed February 27, 1913. Serial No. 751,037.

To all whom it may concern:

Be it known that I, CHARLES D. HAEUSLER, a citizen of the United States, residing at Kressbronn, Bodensee, Wurttemberg, Germany, have invented certain new and useful Improvements in Apparatus for Activating Fluids with the Emanations of Radio-Active Material, of which the following is a specification.

10 My invention relates to improvements in apparatus for activating fluids with the emanations of radio-active material, the object of the invention being to provide improvements of this character which enable 15 a fluid such as water or air to become radio-active through the medium of means compelling the air or gas to flow first through the radio-active material, and then through the fluid to be activated, carrying the emanations from the radio-active material into and 20 depositing them in the fluid to be activated, whereby the latter may become radio-active to any desired degree.

A further object is to provide an apparatus 25 of this character which prevents any possibility of the radio-active material coming into direct contact with the fluid to be activated and which is designed to prevent loss of such material through accident.

30 A further object is to provide an apparatus of the character stated having an improved arrangement of cocks which control the flow of air or gas through the radio-active material and the fluid to be activated.

35 With these and other objects in view, the invention consists in certain novel features of construction and combinations and arrangements of parts as will be more fully hereinafter described and pointed out in 40 the claims.

In the accompanying drawings: Figure 1 is a view in vertical section illustrating one embodiment of my invention. Fig. 2 is a similar view illustrating a modified construction. Fig. 3 is a view in section on the line 3—3 of Fig. 2. Fig. 4 is a view in section on the line 4—4 of Fig. 2. Fig. 5 is a view in section on the line 5—5 of Fig. 2. Fig. 6 is a view in section on the line 6—6 of Fig. 2 with the addition that in this view an inhaling attachment is shown. Fig. 7 is a view in elevation of the plug which may

be used to close the cover when the inhaling attachment is removed. Fig. 8 is a view in section on the line 8—8 of Fig. 2. Fig. 9 is a view in section on the line 9—9 of Fig. 2. Fig. 10 is a view partly in section and partly in elevation illustrating an attachment for the cock case having pipe nipples thereon.

Referring to Fig. 1, 1 represents a receptacle supported upon a suitable base 2 and having a cock 3 at its lower end adapted to discharge into a removable receptacle 4 supported on a base 2. The top of receptacle 1 is formed with three upwardly projecting 65 conical necks 5, 6, and 7, the outside necks 5 and 7 being preferably higher than the central intermediate neck, and in the latter, a plug 8 is located and provided with a ball check valve 9 normally closing a passage 10 70 therein.

A screw plug 11 normally closes an inlet to said passage as clearly shown. In the larger necks 5 and 7, hollow conical plugs 12 and 13 are positioned, and these plugs at 75 opposite sides, are formed with pipe nipples 14. The adjacent nipples 14 of the two plugs 13 are connected by a pipe 15, and the outside nipples of the two plugs are connected to a pipe 16 having means between its 80 ends for compelling a flow of air or gas therethrough.

In Fig. 1, this operative means is indicated in the form of two bulbs 17 and 18, the former acting as a compression bulb and the latter as a suction or vacuum bulb, so that a continuous flow of air may be forced through the apparatus.

The hollow conical plugs support conical cocks 19 and 20, which snugly fit therein and 90 are provided in one side, with ports 21 to register with the nipples 14. Plunger pipes 22 and 23 are formed integrally with the cocks 19 and 20 respectively. The inlet ends of these plunger pipes 22 and 23 are located 95 in the cocks opposite the ports 21, so that when the port 21 registers with one nipple, the inlet end of the plunger pipe will register with the other nipple as clearly shown. These plunger pipes 22 and 23 are formed with 100 valve seats 24 against which float valves 25 are adapted to close. The lower ends of the plunger pipes are provided with relatively small perforations 26 through which the air

or gas is discharged, and the plunger pipe 22 extends into a tubular receiver 27 which may, as indicated in Fig. 1, be integral with the conical plug 12.

5 A removable stopper 28 normally closes an inlet 29 for water or other fluid 31 to be activated, and the active material 30 preferably in solution, is located within the receiver 27.

10 As indicated in the drawings, it is my intention to construct the casing and coöperating parts of non-corrosive material, such for example, as glass and the float valves 25 are also preferably of glass, yet, of course, I am not limited to any particular material.

In operation, the air is caused to circulate through pipe 16 in the direction of the arrows, so that it will flow first downwardly 20 through plunger pipe 22 into the radio-active material 30 in the lower end of said pipe, and also up through the radio-active material in the receiver 27. The air thus impregnated with the emanations of the radio-active material flows through pipe 15, and down through plunger pipe 23 into the fluid 31 to be activated. This air bubbles up through the fluid 31, leaving its radio-active emanations and passes out through cock 20 25 and flows through the same path over and over again until the fluid 31 is rendered radio-active to the desired degree.

The radio-active material 30 is extremely expensive, and the float valves prevent any 30 possibility of the air flowing in the wrong direction which would carry the radio-active material out of the receiver, and by providing a plurality of such float valves, the failure of one or more of such valves to operate correctly, would not materially effect the operation of the apparatus.

In the form of my invention illustrated in Figs. 2 to 10 inclusive, I provide a single cock 32 for controlling the flow of air or gas 45 through the apparatus instead of providing two separate cocks as in Fig. 1. In this form of my invention, I secure on top of receptacle 1, a cover 33 preferably rendered air tight by a cemented packing 34.

50 A top casing 35 closes a central opening in the cover, and this top casing is formed with an internally screw-threaded depending ring 36 into which a tubular receiver 37 is screwed. The receiver 37 in this form of my invention is preferably of metal but coated on its inner and outer surfaces with glass or a similar material 38.

The cock casing is formed with three vertical passages 39, 40, and 41. The first-mentioned passage 39 registers with the end of a threaded coupling 42 which carries the plunger pipe 43 corresponding to the plunger pipe 22 of Fig. 1, and extending down into the receiver 37 where it is provided 65 with a perforated end 44, and between its

ends with valve seats 45 normally closed by float valves 46.

The passage 40 is an inlet passage for the radio-active material 30, and registers with a port 47 in cock 32. The upper end of this 70 passage is normally closed by a screw-plug 48. The passage 41 registers with a coupling 49 screwed into the cock casing, and to which the plunger pipe 50 is secured. This pipe 50 corresponds with the plunger pipe 75 23 of Fig. 1, and is provided with the valve seats 45 and the float valves 46. These parts are given reference numerals differing from Fig. 1 because while they perform a similar function, they are differently constructed. 80

The cock 32 is provided with ports 51 and 52 which are adapted to register with the passages 39 and 41 respectively, and control the flow of air through the plunger pipes. In the several cross sections, the arrangement of the several ports in the cock 32 is clearly shown. In Figs. 3 and 4, for example, it will be seen that the port 51 communicates with a pipe nipple 53 which acts as an inlet for the air or other gas. This 90 air or gas flows downwardly through the plunger pipe 43, thence upwardly through the radio-active material 30 into passage 40 from which it is directed by the cock 32 through a passage 55, and it flows through a passage 56 into the port 52 above referred to, hence, downwardly through the plunger pipe 50 and through the fluid 31 into the upper part of receptacle 1. This air then 95 flows through a port 57 in the cock and communicates with a nipple 54 which acts as an outlet of the apparatus. These nipples 53 and 54 are designed to be coupled to any arrangement of pipes, whereby the air is compelled to circulate through the system as 100 above described. 105

The passage 56 above referred to is preferably formed in a removable plate 58 secured by screws 59 to the cock casing, and when desired, this plate 58 may be removed 110 and a plate 60 substituted therefor. This plate 60 contains nipples 61 so that the activated air may be carried to any desired point for use, and if desired, in a circulating system. 115

While I have referred to the cover 33 as one part, as a matter of fact, it is preferably composed of two pieces secured together by stud bolts 62 and nuts 63, and a removable plug 64 normally closes a threaded opening 65 in the cover. This plug may be removed and a nipple 66 screwed into the opening, and to which an inhaling mask 67 may be connected by a flexible pipe 68 so that inhalations may be taken directly from the 120 apparatus. 125

I would have it understood that in using the terms air, gas, fluid and liquid, that I use these terms in the broadest possible sense, for while the liquid is preferably 130

water, and the gas is preferably air, either of these when activated may be utilized as a fluid for various purposes, and the richness of the fluid may be regulated to suit conditions.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination with a fluid containing receptacle, of a receptacle for radio-active material, radio-active material in said receptacle and means for compelling a passage of gas first through the active material, and then through the liquid, whereby emanations of the active material are imparted to the gas and the liquid, substantially as described.

2. The combination with a receptacle for liquid, a receiver in said liquid adapted to contain radio-active material, radio-active material in said receptacle, means for compelling air to flow through the radio-active material and receive emanations therefrom, and means for directing said air through the liquid in the said receptacle, whereby the emanations received by the air are imparted to the liquid to activate the latter, substantially as described.

3. The combination with a receptacle containing liquid, a receiver in said receptacle containing radio-active material, air pipes extending into the receptacle and the receiver and terminating below the liquid levels in the same, and means for compelling a flow of air through said pipes, substantially as described.

4. The combination with a receptacle containing liquid, a receiver in said receptacle containing radio-active material, air pipes extending into the receptacle and the receiver and terminating below the liquid levels in the same, means for compelling a flow of air through the pipe in the receiver, and thence directing the air from the receiver through the pipe in the first-mentioned receptacle, whereby the emanations of the radio-active material are deposited in the liquid, substantially as described.

5. The combination with a receptacle containing liquid, a receiver in said receptacle containing radio-active material, air pipes extending into the receptacle and the receiver and terminating below the liquid levels in the same, means for compelling a flow of air through said pipes, and means permitting a flow of air in one direction only, substantially as described.

6. The combination with a receptacle containing liquid, a receiver in said receptacle containing radio-active material, air pipes extending into the receptacle and the receiver and terminating below the liquid levels in the same, means for compelling a flow of air through the pipe in the receiver, and thence directing the air from the receiver through the pipe in the first-mentioned receptacle, whereby the emanations of the radio-active material are deposited in the liquid, and means permitting a flow of air in one direction only, substantially as described.

7. The combination with a receptacle containing liquid, a receiver in said receptacle containing radio-active material, air pipes extending into the receptacle and the receiver and terminating below the liquid levels in the same, and means for compelling a flow of air through said pipes, and float valves in said pipes, substantially as described.

8. The combination with a receptacle containing liquid, a receiver in said receptacle containing radio-active material, air pipes extending into the receptacle and the receiver and terminating below the liquid levels in the same, means for compelling a flow of air through the pipe in the receiver, and thence directing the air from the receiver through the pipe in the first-mentioned receptacle, whereby the emanations of the radio-active material are deposited in the liquid, and float valves in said pipes, substantially as described.

9. The combination with a receptacle containing liquid, a tubular receiver in said receptacle containing radio-active material in solution, plunger pipes located in the receptacle and in the receiver and extending below the liquid levels in both, said pipes adapted to discharge at their lower ends, and means for compelling a continuous flow of air in series first through the plunger pipe in the receiver and then through the plunger pipe in the receptacle, substantially as described.

10. The combination with a receptacle containing liquid, a tubular receiver in said receptacle containing radio-active material in solution, plunger pipes located in the receptacle and in the receiver and extending below the liquid levels in both, said pipes adapted to discharge at their lower ends, means for compelling a continuous flow of air in series first through the plunger pipe in the receiver and then through the plunger pipe in the receptacle, said plunger pipes having valve seats therein, and float valves in said pipes, substantially as described.

11. The combination with a receptacle adapted to contain liquid, of a receiver in the receptacle adapted to contain radio-active material, plunger pipes located in the

- receiver and in the receptacle and discharging below the liquid levels in both, means for compelling a continuous flow of air in series first through the plunger pipe in the receiver and then through the plunger pipe in the receptacle and a single cock controlling the flow of gas through said receptacle, receiver and pipes, whereby the rapidity of the passage of air through the liquids may be regulated and whereby communication between the receiver for the radio-active material may be entirely cut off from the remainder of the apparatus, substantially as described.
15. In an apparatus for activating fluids with emanations of radio-active material, the combination of a main receptacle provided with a wide mouth, a metal closure for said mouth, a metallic receptacle for radio-active material fixed to and depending from said closure, means for producing a current of air or gas first through the receptacle for the radio-active material and then through the main receiver and means for cutting off communication between said receptacle for the radio-active material and the remainder of the apparatus and for securely sealing the last mentioned receptacle, substantially as described.
16. In an apparatus for activating fluids with emanations of radio-active material, the combination of a main receptacle provided with a wide mouth, a metal closure for said mouth, a metallic receptacle for radio-active material fixed to and depending from said closure, said receptacle having its inner and outer faces coated with glass or similar inert material, means for producing a current of air or gas first through the receptacle for the radio-active material and then through the main receiver and means for cutting off communication between said receptacle for the radio-active material and the remainder of the apparatus and for securely sealing the last mentioned receptacle, substantially as described.
17. In an apparatus for activating fluids with emanations of radio-active material, a main receptacle provided with a wide mouth, a metallic closure for said mouth provided with a depending circular flange, a receptacle for radio-active material provided with an open upper end threaded into said flange, a pair of plunger pipes fixed to and depending from said closure, one of said pipes extending into the receptacle for the radio-active material and the other into the main receptacle and means for creating a circulation of air or gas first through the receptacle for the radio-active material and then through the main receptacle, substantially as described.
18. In a device for activating fluids with emanations of radio-active material, a main receptacle having a wide mouth, a closure for said mouth, a receptacle for radio-active material fixed to and depending from said closure, said closure being formed with an enlargement on its upper face, a valve in said enlargement, a pair of plunger pipes fixed to and depending from said closure, one of said pipes depending into the receptacle for the radio-active material, ducts leading from each of said receptacles and from each of said plunger pipes into said enlargement, means for creating a fluid current through said ducts, pipes and receptacles and a valve in said enlargement con-
- 5 10 15 20 25 30 35 40 45 50 55 60
- 65 70 75 80 85 90 95 100 105 110 115 120 125

trolling said ducts and adapted to securely close the receptacle for the radio-active material, substantially as described.

19. In an apparatus for activating fluids with emanations of radio-active material, a main receptacle, a receptacle for radio-active material, means for creating a fluid current first through the receptacle for the radio-active material and then through the main receptacle and a cock on said main receptacle for drawing off the activated fluid, substantially as described.
20. In an apparatus for activating fluids with emanations of radio-active material, a main receptacle and a receptacle for radio-active material, in combination with a fluid

circulating system including a pair of plunger pipes depending into said receptacles respectively and means for creating a circulation of fluid first through the receptacle for the radio-active material and then through the main receptacle, inhaling apparatus, and means for attaching said inhaling apparatus in series with the circulating system, substantially as described.

21. In testimony whereof I have signed my name to this specification in the presence of two subscribing witnesses.
